UNITED STATES PATENT OFFICE.

JAMES SUTHERLAND, OF NOME, DISTRICT OF ALASKA.

THAWING-POINT.

No. 839,227.

Specification of Letters Patent.

Patented Dec. 25, 1906.

Application filed March 31, 1906. Serial No. 309,120.

To all whom it may concern:

Be it known that I, JAMES SUTHERLAND, a citizen of the United States, residing at the city of Nome, District of Alaska, have invented certain new and useful Improvements in Thawing-Points, of which the following is a specification.

The invention relates to such improvements; and it consists of the novel construction and combination of parts hereinafter described and subsequently claimed.

Reference may be had to the accompanying drawings, and the reference characters marked thereon, which form a part of this specification.

Similar characters refer to similar parts in the several figures therein.

Figure 1 of the drawings is a side view of my improved thawing-point. Fig. 2 is a central longitudinal section of the same. Fig. 3 is a plan view of the clamp-plates detached.

It is well known that gold is found distributed in gravel-banks and in gravel channels and drifts at more or less depths in Alaska and Northern Canada, where the gravel is perpetually frozen.

Where the gold exists in sufficient quantities to justify the expense, the gravel is thawed by steam, so as to be extracted, and is then placed on dumps on the surface, where the dumps are afterward washed and sluiced with water and the gold saved as soon as the dumps have been thawed by natural means. A large percentage of placer-mining in Alaska is done in this way.

The method of applying the steam in thawing the gravel is to drive metal points into the face of a drift where the ground is frozen and to inject steam from a boiler through the points, which are made hollow for this purpose, into the gravel until the ground becomes sufficiently thawed.

My invention relates to improvements in thawing-points adapted for use for the purpose stated; and the principal objects of the invention are to provide and maintain during the use of the point a tight connection between the body of the point and the hose or pipe connecting the point with a source of steam-supply.

Referring to the drawings, wherein my invention is shown in its preferred form, 1 represents the head of the point, which is formed of cast or wrought metal, having on its outer end an impact-surface adapted to receive the

impact of a sledge or mall in driving the point into the ground. The head is formed with a chamber 2, from which a lateral aperture 3 extends to the periphery of the head, and the aperture 4 extends to the lower end of the head, being adapted to receive the shank or body 5 of the point which is welded or otherwise secured therein. The shank or body 5 of the point is formed of heavy metal pipe or tubing several feet in length, having its lower end tapered or conical in form, constituting a penetrating-point, as shown at 6, at the apex of which is the outlet-aperture 7. Screwed or otherwise secured in the lateral aperture 3 is one end of a pipe or nipple 8, to the other end of which is connected a hose or pipe 9, leading from a steam-boiler. The nipple 8 is in the form of an elbow having its outer end extending upwardly parallel with and in close proximity to the head 1, with which it is connected by a clamp comprising a pair of clamp-plates 10 and 11, formed to embrace between them both the head 1 and the hose-inclosed end of the nipple 8 and adapted to be tightly drawn together by means of the bolts 12 and nuts 13, the same clamps serving to secure the hose upon the end of the nipple and to support and brace the nipple and secure it to the head.

The clamp may be further connected with the head by inserting screws or pins 14 through apertures 15, formed in the clamp-plates, and into apertures formed to receive them in the head 1.

In the use of the device the point is driven into the ground to the desired distance by the blows of a sledge or mall applied to the upper end of the head 1, after which steam is supplied through the hose 9, passing through the nipple and chamber 2 and out through the aperture 7 at the lower end of the point into the surrounding gravel. The point is allowed to remain in this position for several hours, during which time steam is continuously injected through the point into the gravel until the desired result is obtained.

By making the nipple in the form of an elbow, as shown, I am able to maintain the hose connection in a position parallel with the direction of the force applied with the hammer or mall to the head in driving the point into the frozen ground, as well as to connect the end of the nipple with and support it by the neighboring head 1, which is parallel therewith, and I am able to greatly

relieve the screw connection or other connection between the inner end of the nipple and the head from strain, due to overcoming the inertia of the nipple and hose connection when the head is subjected to the blows of the sledge or mall. I am thus able to prevent the escape, loosening, or breaking of the nipple at its point of connection with the head, and thereby loss of steam and the resultant interference which would occur with the work of the miners.

The head 1 and body or shank 5 of the point are, in effect, one piece and may be so made, if desired.

15 What I claim as new, and desire to secure by Letters Patent, is—

1. In a thawing-point, the combination with the head having on one end a penetrating-point, and on the opposite end an impact-surface, and provided intermediately of its ends with an inlet-aperture in its side and with a fluid passage-way extending from said side aperture to an aperture near said point; of an elbow-shaped metal nipple having its inner end at right angles to the head and secured in said aperture, and its outer end extending parallel with the axis of the head; and a supporting connection between the outer end of the nipple and the head.

2. In a thawing-point, the combination 30 with the head having an inlet-aperture in its side; of an elbow-shaped nipple having its inner end secured in said aperture and its outer end extending parallel with the axis of the head; a hose inclosing the outer end of 35 the nipple; and a clamp embracing said hose and hose-inclosed end of the nipple and secured to said head.

3. In a thawing-point, the combination with the head having an aperture in its side; 40 of an elbow-shaped nipple having its inner end secured in said aperture and its outer end extending parallel with the axis of the head; a hose inclosing the outer end of the nipple; a pair of clamp-plates adapted to receive between certain opposed portions thereof said head, and between certain other opposed portions thereof said hose and the hose-inclosed end of the nipple; and screw mechanism for securing said clamp-plates together 45 and upon the respective inclosed members.

In testimony whereof I have hereunto set my hand this 11th day of January, 1906.

JAMES SUTHERLAND.
